CARD FILING EQUIPMENT

George C. Bruen, Chicago, Ill., assignor, by direct and mesne assignments, of seventy and five-tenths per cent to Sophie E. Bruen, Chicago, Ill., five per cent to Edna V. Dickinson, Highland Park, Ill., nine per cent to Sarah M. Bullock, Wilmette, Ill., ten and five-tenths per cent to G. A. Stuart, Washington, D. C., two per cent to Jay Fisher, Chicago, Ill., one per cent to Marie Thoenen, Elmwood Park, Ill., one per cent to George H. Frederickson, Chicago, Ill., and one per cent to E. M. Thorsen, St. Joseph, Mo.

Application August 4, 1945, Serial No. 608,911

6 Claims. (Cl. 129—16)

1

The present invention relates to card filing equipment, and is particularly concerned with card filing trays of the type which are adapted to form a removable part of some more complex support, such as a wheel, or which are adapted to be used separately as card filing units, to be supported upon a desk or any other work support.

One of the objects of the invention is the provision of an improved form of card filing tray which is so constructed that the cards may be conveniently removed, one by one, or in a separate stack of cards, or all of the cards may be removed in their entirety with the securing devices that are removably carried by the tray.

Another object of the invention is the provision of an improved card filing equipment having removable card-supporting devices which are adapted to support cards of the type having one or more apertures and a slot, or which are merely provided with a round aperture.

Another object of the invention is the provision of an improved form of portable card tray which is provided with end walls that are adapted to support the cards in conventional open book form at practically any point where the operator may separate the cards.

Another object of the invention is the provision of an improved card tray which utilizes a minimum amount of critical materials, such as metals, and which is adapted to be constructed at a very low cost, so that it may be sold within a price range that makes it available to a vast number of users.

Another object of the invention is the provision of an improved card tray which is sturdy, simple in construction, provided with a removable card-securing unit, and which is adapted to support a maximum number of cards in position for convenient use at a minimum expense.

Another object of the invention is the provision of improved card tray structures in which the cards may be wholly supported on the supporting rails or rods which provide a minimum area of contact and a minimum amount of friction to the movement of the cards, as distinguished from the devices in which the cards engage the base of the tray as well, which greatly increases the friction to the movement of cards.

Other objects and advantages of the invention will be apparent from the following description

2

and the accompanying drawings, in which similar characters of reference indicate similar parts throughout the several views.

Referring to the drawings, of which there are three sheets,

Fig. 1 is a view in perspective of a card tray embodying the invention, equipped with two types of cards;

Fig. 2 is a fragmentary top plan view of the left end of the tray of Fig. 1, in partial section, on the plane of the line 2—2 of Fig. 3;

Fig. 3 is a longitudinal elevational view in partial section, taken on the plane of the line 3—3 of Fig. 2;

Fig. 4 is a fragmentary transverse sectional view, taken on the plane of the line 4—4 of Fig. 3, looking in the direction of the arrows;

Fig. 5 is a fragmentary sectional view, taken on the plane of the line 5—5 of Fig. 2, looking in the direction of the arrows;

Fig. 6 is a fragmentary sectional view, taken on the plane of the line 6—6 of Fig. 3, looking in the direction of the arrows;

Fig. 7 is a fragmentary sectional view, taken on the plane of the line 7—7 of Fig. 3, looking in the direction of the arrows;

Fig. 8 is a bottom plan view of the cards and card-supporting unit, removed from the tray.

Referring to Fig. 1, 10 indicates in its entirety a tray assembly which is provided with the card-securing and supporting unit 11 for carrying a plurality of different types of cards 12, 13. The tray proper, indicated at 14, preferably consists of a substantially rectangular base 15, which may be constructed of various materials, preferably nonmetallic, such as plastic, and the base is provided with a pair of diagonally and outwardly extending end walls 16, 17.

The end walls 16, 17 comprise plastic members, which preferably taper from the bottom toward the top in thickness, and the end walls are preferably substantially rectangular in elevation. The outer surface of each end wall may be provided with a substantially horizontal rib 18 located in a middle position with respect to the top and bottom of each end wall, and below the rib 18 each end wall may have a depression or enlarged groove 19 that is capable of receiving the fingers and permitting the operator to grasp the end wall more firmly.

Thus the hand may be applied by placing the thumb over the top and on the inside flat surface 20 of an end wall, the fingers extending downwardly on the outside over the rib 18 into the groove 19. Each end wall 16 or 17 is provided with a lower horizontal attaching surface 21 and a vertical attaching surface 22 for engaging the end of the base 15, and the surfaces 21, 22 are at right angles to each other and so oriented with respect to the inner surface 20 of the end wall that the inner surface 20 extends diagonally upward and outward when the base 15 fits into the corner that is provided by the surfaces 21, 22.

The end walls may be secured to the base by a plurality of screws 23, which pass through apertures 24 in the base and are threaded into the end wall.

The end walls 16, 17 are preferably recessed at the lower part of their inner diagonal surfaces 20 to provide suitable supports and securing means for holding the card-supporting and securing unit 11.

The card-securing unit 11 may consist of a round rod of metal or a suitable heat moldable plastic, such as "Lucite," which is bent to substantially U shape, having a substantially straight yoke 25 and a pair of parallel legs 26, 27.

The yoke 25 is adapted to be received in a horizontally extending groove 28 located in the end wall 17. The groove 28 may be of substantially rectangular shape in cross section, as shown in Fig. 3, and it may be deep enough to receive the yoke 25 and a small portion of the adjacent leg portions 26, 27.

The groove 28 is preferably located at such an elevation above the base 15 that the rod legs 26, 27 are located to engage the tops of the apertures 29 in the cards when the cards are supported on the tray.

The other end wall 16 has its inner surface 20 provided with a pair of inwardly extending horizontal bores 30, 31 located to receive the ends of the rod legs 26, 27 when the yoke 25 is bottomed in the groove 28.

The end wall 16 is also provided with a horizontally extending groove 32, which is preferably rectangular in cross section and located immediately above the bores 30, 31 that receive the legs 26, 27. The groove 32 is adapted to receive the latching member 33, comprising a metal bar which is carried by a spring, pressed plunger 34.

The bar 33 preferably has in the end adjacent the groove 32 a cross slot of a size to receive the bar 33, which bar extends through the slot with a tight frictional fit and is secured therewith by soldering, welding, or other convenient fastening means.

In order to accommodate the plunger 34 the end wall 16 is also provided with a through bore 37 and a counterbore 38. The counterbore 38 has a metal washer 39 at its end to provide a seat for the helical compression spring 40, which urges the latching bar 33 into latching position.

The plunger 34 extends through the bore 37 and is preferably provided with a reduced threaded portion 41 that is threaded into a threaded bore 42 in a knob 43 of wood or initially heat moldable plastic or other suitable material.

The depth of the groove 32 is sufficient to receive the bar 33 when the plunger 34 is pulled outward, and to permit the bar 33 to clear the ends of the legs 26, 27. The bores 30, 31 are provided with vertical openings 44 on their upper side, these openings having a vertical wall 45, and comprising vertical grooves which are of the same

width as the bores 30, 31, so that when the plunger 34 and bar 33 are withdrawn, the legs 26, 27 may move upward out of the bores 30, 31 via the grooves 44.

In some embodiments of the invention I may dispense with a brace 46 which extends from one leg 26 to the other leg 27 and holds the legs in parallel position. Such a brace is unnecessary where the legs are made of stiff metal rod and adapted to hold their parallel position due to the strength of the yoke 25.

The transverse brace 46 may consist of a strap of the same material as the legs 26, 27, such as, for example, metal; and this strap has a pair of upwardly turned end portions 47, 48 which are secured in the narrow slots 49 formed in the bottom of each leg 26, 27.

The end portions 47, 48 may be held by a tight frictional fit in slots 49, or they may be soldered, welded, or otherwise secured therein.

The end portions 47, 48 are long enough so that the transverse body portion of the brace 46 is located below the cards 12 or 13 when they are mounted on the rod legs 26, 27. The thickness 25 of the strap of which the brace 46 is made is preferably such that the vertically extending portions 47, 48 are adapted to pass the slots 50 in the cards with a clearance.

When the transverse brace 46 is omitted, the present card-supporting and securing unit may be used with cards having only round holes and having no slots 50. The cards utilized with my tray may be of any desired size, but they are preferably large enough in relation to the spacing 35 of the legs 26, 27 so that a pair of apertures 29 may be provided, having downwardly extending slots 50 for receiving the legs 26, 27 and brace portions 47, 48.

The apertures 29 are preferably slightly wider 40 than the diameter of the legs 26, 27 in a horizontal direction, but still larger in size in a vertical direction, so that these apertures are oval in shape and have a relatively large clearance below the legs 26, 27.

This permits any card to be supported on the rods 26, 27 in a diagonal position substantially parallel to the inside surfaces 20 of the end walls 16, 17 without binding. The oval aperture 29 corresponds to a diagonal cross section of the rods 26, 27, with an additional clearance about the rods.

Each side of the base 15 is preferably rabbeted at its upper outer corner so that the base is provided with edge flanges 53 of reduced thickness, 55 these flanges extending backward to the vertical surface 54. The end walls 16, 17 may be similarly rabbeted so that they are provided with grooves 55, 56 on each side, and the edge flanges 53 may thus be used as retaining members for 60 slidably engaging guides upon any kind of a support, such as a supporting frame or a rotary tray-supporting member.

The operation of my tray is substantially as follows: Each pack of cards is preferably provided with end plates 51, 52 of similar size and shape to the cards, and provided with similar apertures 29 and slots 50. These end plates may be made of stiff fiber, such as indurated fiber, and they are adapted to provide a measure of protection for the end cards and to provide a backing against which the end cards may lie, even when the supporting and securing unit 11 is removed from the base of the tray.

The present card-supporting tray is portable, as it may be carried by either of its end walls,

which are conveniently shaped to be engaged by the hand and held by the ends of the fingers. The tray may be supported upon a desk or other work-supporting surface, or it may form a part of a rotary card filing apparatus, upon which it is secured.

When it is desired to refer to any of the cards, this may be done by means of suitable separators and indicia; and due to the shape of the apertures and rods relative to each other and to the diagonal supporting surfaces 20 on each of the end walls, the cards separate radially at any point like a book except that there is no curving of the cards, which extend diagonally upward on each side of the opening that is made in the stack.

This makes a very convenient assembly for reference and for making entries in the record, and saves a great deal of time.

The apertures 29 are preferably spaced from each other by a distance greater than the distance from either aperture to the edge of the card so that any card may be removed from the two legs 26, 27 and displaced laterally toward the right or left in Fig. 1, and secured only upon one of the legs, with the card projecting laterally to give an indication of the condition of any account.

When it is desired to remove a pack of cards from the card-supporting and securing unit 11, that unit may be released by pulling on the plunger knob 43 until the legs 26, 27 can be lifted. Then the cards in a stack may be slid endwise off the rods 26, 27.

If it is desired to remove one or more separate cards, this can be done by merely twisting the cards slightly and pulling upward, whereupon the curved bottom surfaces of the rods 26, 27 will cam the adjacent portions of the card upward at the slots 50 and permit the removal of a single card or a few cards.

When it is desired to remove the entire stack of cards from the tray, this may be done by pulling on the plunger knob 43 and lifting the legs 26, 27 out of their bores until the yoke 25 may be withdrawn from its slot 28 in the end wall 17. Then the brace 46 may serve as a convenient handle by means of which the entire assembly of cards and the supporting unit 11 may be held in one hand, the yoke preventing the cards from sliding off the other ends of the legs 26, 27.

The present card-supporting tray is simple and has a minimum number of parts, and utilizes a minimum amount of metal. Rods of thermally moldable plastic may be used instead of metal, thereby further reducing the need for metal in the manufacture of this device. Due to the simplicity of the device, it may be manufactured at a low cost, and it involves a minimum number of machining operations in its manufacture.

The tray is adapted to hold the cards whether they are in vertical position or whenever the tray is partially or wholly inverted, and whenever desired the complete card unit may be removed from the tray, or any number of cards may be removed in a stack, with a minimum amount of effort.

Another important feature of the invention, which may or may not be utilized in any of the modifications of this invention is the full support of the cards on the card supporting members 26, 27 out of contact with the upper surface 14 of the base 10 in such manner that there is no friction to the movement of cards between the base and the cards, and the friction involved

in sliding one or more cards on the supporting members 26, 27 is very greatly reduced over the devices of the prior art. Since the apertures in these cards are larger than the round supporting members 26, 27, there is only a line of contact at the point of tangency between the aperture in the cards and the round supporting member.

In so far as one card is concerned, it is practically a point contact, and this greatly reduces the friction so that the cards slide readily from one plate to another when taken singly or in batches or handfuls. This is best illustrated in Fig. 3, where it can be seen that the bottom of the cards is out of contact with the upper surface 14 of the base, and also in Fig. 4.

While I have illustrated a preferred embodiment of my invention, many modifications may be made without departing from the spirit of the invention, and I do not wish to be limited to the precise details of construction set forth, but desire to avail myself of all changes within the scope of the appended claim.

Having thus described my invention, what I claim as new and desire to secure by Letters Patent of the United States, is:

1. A card filing tray comprising a base having a stable supporting surface, said base being provided at each of its ends with an upwardly extending wall member, a card supporting and securing unit removably mounted on said base, said unit including a rod extending longitudinally of and substantially parallel to said base and spaced therefrom, whereby a multiplicity of cards provided with apertures for receiving said rod may be slidably supported upon said rod in position to be opened at any convenient point for reference, the stacks of cards on either side of the opening resting against said end walls, said supporting and securing unit having its rod formed to substantially U shape with side legs and a yoke portion removably fitting into a slot type recess in one of said walls, said recess opening longitudinally of the base, the ends of said U-shaped rod remote from the yoke portion engaging in recesses opening upwardly and longitudinally of the base at a distance therefrom in the other of said walls, a lateral brace extending between said side legs and having upwardly extending end flanges secured to the side legs near the ends thereof, said lateral brace providing support for the legs at substantially the level of the latter mentioned recesses, and the latter mentioned wall being provided with latching means including a movable latching bar for simultaneously engaging both ends of said rod, said latching bar having a latching position overlying the ends of said U-shaped rod in said recesses and a retracted position in which the said ends of the rods are removable from the recesses.
2. A card filing tray comprising a base having a stable supporting surface, said base being provided at each of its ends with an upwardly extending wall member, a card supporting and securing unit removably mounted on said base, said unit including a rod extending longitudinally of and substantially parallel to said base and spaced therefrom, whereby a multiplicity of cards provided with apertures for receiving said rod may be slidably supported upon said rod in position to be opened at any convenient point for reference, the stacks of cards on either side of the opening resting against said end walls, said supporting and securing unit having its rod formed to substantially U shape with a yoke portion removably fitting into a slot type recess in

one of said walls, the ends of said U-shaped rod engaging in upwardly and longitudinally opening recesses in the other of said walls, said latter wall being provided with latching means including a cross bar for simultaneously engaging both ends of said rod, said cross bar being supported for linear movement in a recess in said latter wall by a plunger extending through said wall and having manually actuatable means on its exposed end, and a spring biasing said cross bar to a position overlying the ends of said U-shaped rod.

3. A card filing tray, comprising a base having a stable supporting surface, said base being provided at each of its ends with an upwardly extending wall member, a card supporting and securing unit removably mounted on said base, said unit including a longitudinally extending rod extending substantially parallel to said base and spaced therefrom, whereby a multiplicity of cards provided with apertures for receiving said rod may be slidably supported upon said rod in position to be opened at any convenient point for reference, the stacks of cards on either side of the opening resting against said end walls, said end walls being tapered from the bottom toward the top and being provided with inner outwardly sloping plane surfaces for engaging the end cards and determining the open position of the cards to which reference is made, said supporting and securing unit comprising a rod of substantially U-shape, the yoke of said U serving to retain the cards on the unit when held with the legs extending upwardly, said unit also being provided adjacent the ends of said legs with a transversely extending brace having a body portion extending laterally between the legs and their flanges secured at their ends to the legs to hold said body portion in spaced relationship to the legs.

4. A card filing tray, comprising a base having a stable supporting surface, said base being provided at each of its ends with an upwardly extending wall member, a card supporting and securing unit removably mounted on said base, said unit including a longitudinally extending rod extending substantially parallel to said base and spaced therefrom, whereby a multiplicity of cards provided with apertures for receiving said rod may be slidably supported upon said rod in position to be opened at any convenient point for reference, the stacks of cards on either side of the opening resting against said end walls, said end walls being tapered from the bottom toward the top and being provided with inner outwardly sloping plane surfaces for engaging the end cards and determining the open position of the cards

5 to which reference is made, said supporting and securing unit comprising a rod of substantially U-shape, the yoke of said U serving to retain the cards on the unit when held with the legs extending upwardly, said unit also being provided adjacent the ends of said legs with a transversely extending brace, said brace having a body portion carried by two upwardly extending flanges having their ends secured to the lateral mid-portions 10 of the legs on the sides thereof adjacent the base, said flanges being of a length such that said body portion clears the cards, and said flanges being adapted to be passed by slots in the cards.

5. A card filing apparatus, comprising a substantially U-shaped rod member formed with a pair of parallel legs joined by a transversely extending brace made of relatively thin flat strip material and located near the ends of said legs, said brace having a body portion spaced below 15 said legs by a pair of upwardly extending attaching flanges having their ends secured to said legs with the planes of the flat strip material extending longitudinally along the mid-portions of the legs, said body portion serving as a handle and brace for maintaining the parallelism of said legs.

6. A card filing apparatus, comprising a substantially U-shaped rod member formed with a pair of parallel legs joined by a transversely extending brace located near the ends of said legs, said brace having a body portion spaced below 20 said legs by a pair of upwardly extending attaching flanges secured to said legs, said body portion serving as a handle and brace for maintaining the parallelism of said legs, said legs being slotted to receive the ends of said securing flanges, which are located in said slots.
